INVENTOR.

William H. West
BY
Douglas S. Webster
ATTORNEY

UNITED STATES PATENT OFFICE.

WILLIAM H. WEST, OF STOCKTON, CALIFORNIA.

VALVE-CAP.

1,353,878.

Specification of Letters Patent. Patented Sept. 28, 1920.

Application filed September 17, 1917. Serial No. 191,699.

To all whom it may concern:

Be it known that I, WILLIAM H. WEST, a citizen of the United States, residing at Stockton, in the county of San Joaquin, 5 State of California, have invented certain new and useful Improvements in Valve-Caps; and I do declare the following to be a full, clear, and exact description of the same, reference being had to the accompanying 10 drawings, and to the characters of reference marked thereon, which form a part of this application.

This invention relates to improvements in valve caps for use on pneumatic tires, where- 15 by the caps may be fastened and removed without the usual waste of time due to having to screw the same on the long threaded valve stem as is now the case. Very often, it also happens that the threads of the valve 20 stem or of the cap itself become dirty and deteriorated, making it hard to remove or replace the common style of cap, and the operator generally in a hurry, uses some tool and ruins both cap and stem, the re- 25 sult being much future trouble and loss of time.

The object of my invention is to provide a cap which can be easily and quickly re- 30 moved and replaced perfectly secure, and 30 which shall become a comfort instead of a hindrance to all users of motor vehicles.

A further object of the invention is to 35 produce a simple and inexpensive device and yet one which will be exceedingly effective for the purposes for which it is designed.

These objects I accomplish by means of 40 such structure and relative arrangement of parts as will fully appear by a perusal of the following specification and claims.

45 In the drawings similar characters of reference indicate corresponding parts in the several views.

Figure 1 is a longitudinal section through my improved valve cap, loose on the valve 45 stem.

Fig. 2 is the same cap, also on the valve stem partly broken and in section, showing the parts in locked position.

Fig. 3 is a perspective view of the valve 50 cap showing more clearly the flattened sides and its lower part.

Referring now more particularly to the characters of reference in the drawings, the 55 numeral 1 designates the valve stem, which is provided with the usual thread 1^a, and flattened on two opposite sides as at 1^b.

Numeral 2 represents my improved valve cap casing, its lower end being slightly pressed in as at 3, having for a small portion of its circumference, threads 3^a corre- 60 sponding with the threads 1^a of the stem. Opposite the threads 3^a is a small rectangular chamber 4 in which is a slidable locking block 5 provided at its lower end with threads 5^a corresponding to the threads 1^a 65 of stem 1. Secured to this block 5 is a pin 6 sliding through the opening 7, on the rear end of the chamber 4. Between the block 5 and rear end of chamber 4 is a coil spring 8 tending to force the block 5 toward the 70 threads 3^a. In order to hold the block 5 away from engagement with the threads 1^a of the stem 1 when removing the cap, I provide a small plate 9 hinged to pin 6 near its outer end, as at 10, and a slight notch 11 75 holds this plate 10 when in unlocked position.

To keep my improved valve cap from coming unscrewed after being placed, as the new ones now in use are liable to do, I flatten the 80 two opposite sides 3^b between the threads 3^a and chamber 4 as illustrated in Fig. 3 of the drawing, making it impossible to revolve around the valve stem 1. To remove my im- 85 proved valve cap, I raise the plate 9 as shown in Fig. 1. This operation draws the block 5 into the chamber 4 and leaves a clear space between the stem 1 and cap casing 2, permitting the valve cap to be slipped off and on very quickly. 90

From the foregoing description it will be readily seen that I have produced such a device as substantially fulfills the object of the invention as set forth herein.

While this specification sets forth in de- 95 tail the present and preferred construction of the device, still in practice such deviations from such detail may be resorted to as do not form a departure from the invention, as defined by the appended claims. 100

Having thus described my invention what I claim as new and useful and desire to secure by Letters Patent is:

1. In a device of the class described, a cap body and a manually operable locking 105 pin having its engaging portion arranged near the open end of the cap and means to yieldingly hold the same in a locking position and other means for locking the pin in an unlocked position. 110

2. In a device of the class described, a cap body and a manually operable device

comprising a sliding locking pin, a spring to yieldingly hold the pin in a locked position, and a lever pivoted to said pin arranged to lock the pin in an unlocked position.

3. In a device of the class described, a cap body, a manually operable device for locking the cap to the stem comprising a rec-

tangular locking pin guided to slide in a plane at an angle to the axis of the cap body, a spring to yieldingly hold the pin in a locked position and a lever pivoted to the pin to lock the pin in an unlocked position against the tension of the spring.

In testimony whereof I affix my signature.

WILLIAM H. WEST.
